CLAIM

The ornamental design for a curved beading needle, as shown and described.

DESCRIPTION

FIG. 1 is a perspective view of the curved beading needle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of the curved beading needle taken along line 8 as illustrated in FIG. 1.

1 Claim, 8 Drawing Sheets
